(57) **CLAIM**

The ornamental design for a double capture channel member for a modular building, as shown and described.

DESCRIPTION

FIG. 1 is a perspective view of a double capture channel member for a modular building showing my new design, according to a first embodiment.

FIG. 2 is a second perspective view of the channel member of FIG. 1.

FIG. 3 is a front view of the channel member of FIG. 1.

FIG. 4 is a rear view of the channel member of FIG. 1.

FIG. 5 is a left side view of the channel member of FIG. 1.

FIG. 6 is a right side view of the channel member of FIG. 1.

FIG. 7 is a top view of the channel member of FIG. 1.

FIG. 8 is a bottom view of the channel member of FIG. 1.

FIG. 9 is a perspective view of a double capture channel member for a modular building showing my new design, according to a second embodiment.

FIG. 10 is a second perspective view of the channel member of FIG. 9.

FIG. 11 is a front view of the channel member of FIG. 9.

FIG. 12 is a rear view of the channel member of FIG. 9.

FIG. 13 is a left side view of the channel member of FIG. 9.

FIG. 14 is a right side view of the channel member of FIG. 9.

FIG. 15 is a top view of the channel member of FIG. 9; and,

FIG. 16 is a bottom view of the channel member of FIG. 9. The centrally located break and separation, illustrated at least in part by the centrally located pair of adjacent, jagged lines, in FIGS. 1, 2, 9 and 10 forms no part of the claimed design except for indicating indeterminate length. The absence of such break lines in other Figs. shall not indicate a dimensional restriction; rather, relative length of all frame members in indeterminate.
